UNITED STATES PATENT OFFICE

2,529,343

THREADED SELF-LOCKING DEVICE

Anthony H. Lamb, Hillside, N. J., assignor to
 Weston Electrical Instrument Corporation,
 Newark, N. J., a corporation of New Jersey

Application March 17, 1945, Serial No. 583,237

1 Claim. (Cl. 151—38)

1

This invention relates to threaded self-locking devices, and more particularly locknuts or lockscrews that afford a "follow up" or resilient clamping of the connected parts.

The invention is not limited in its application to a particular field or to a particular size or range of sizes but it has been especially useful in the manufacture and servicing of precision electrical instruments and instrument type relays. The types of locknuts and lockscrews that are now manufactured commercially or that have been proposed in the past are not adapted for use in precision instruments for a number of reasons. None of the present commercial types provides the resilient clamping that is essential where plastic parts or gaskets are to be held under compression. Furthermore, none of the prior locknuts and lockscrews can be manufactured in small sizes to meet the design requirements for electrical instruments and relays.

Some of the nuts employed in instrument relays have an internal diameter of 10 mils, an external diameter of 30 mils, and 200 threads to the inch. It is obviously impossible to recess a nut of this minute size to receive a fibre or spring washer and the practice therefore has been to employ separate washers of the resilient splitting type. The lockwashers were stamped from thin sheet metal and in the smaller sizes had a thickness of about 5 mils and an outside diameter of some 30 mils. These minute lockwashers must be separately handled in the manufacture and servicing of instruments and relays, and washers of the wrong size or shape have been used at times and quite often lockwashers have been lost in the instrument and not recovered. There are approximately thirty lockwashers in some relays and the separate handling of these washers adds materially to manufacturing costs, and may result in defective operation when lockwashers are lost within the instrument or relay.

Objects of the present invention are to provide unitary lockwasher-threaded device assemblies that eliminate the disadvantages of the prior assemblies in which separate resilient lockwashers were employed. An object is to provide self-locking threaded devices, nuts or screws, in which resilient lockwashers are brazed, soldered or welded to the threaded devices. A further object is to provide self-locking and resilient threaded devices that may be manufactured in sizes far smaller than has been possible in the past.

These and other objects and advantages of the invention will be apparent from the follow-

2

ing specification when taken with the accompanying drawing in which:

Fig. 1 is a plan view of an instrument type relay in which parts are resiliently clamped in place by threaded self-locking devices embodying the invention;

Fig. 2 is a fragmentary perspective view of the casing and cover plate of the relay shown in Fig. 1;

10 Figs. 3 to 5 are side elevations, on a greatly enlarged scale, of different forms of unitary lock-washer-nut assemblies embodying the invention;

15 Figs. 6 to 8 are end elevations, as seen from the lockwasher ends, of the locknuts illustrated in Figs. 3 to 5, respectively.

Fig. 9 is a side elevation of a lockscrew embodying the invention; and

Fig. 10 is an end elevation of another form of locknut in which a short locking member is used.

20 As shown in Figs. 1 and 2, an instrument type relay includes a coil 1 pivotally mounted in the gap between the ends 2, 2 of a permanent magnet and carrying a contact arm 3 that cooperates with stationary contacts 4, 4' to close a circuit under preselected operating conditions. A considerable number of mechanical and electrical connections in such relays have been of the screw and nut type with separate resilient or split lockwashers but, for purposes of illustration, the drawing shows only the novel threaded connections at the exterior of the casing of a small relay of the type that is described and claimed in my copending application Ser. No. 555,696, filed Sept. 25, 1944, "Relay Circuits and Relays,"

35 which matured into Patent No. 2,440,861 on May 4, 1948. This relay differs from prior practice in that an inadvertent closure of the relay circuits is positively prevented by resilient blocking arms 5, 5' mounted on the transparent cover 6 of the instrument case, the blocking arms having dependent portions 7, 7' that limit the displacement of contact arm 3 to a small angle α so long as the resilient arms are tied to each other by a fusible wire 8. The resilient arms 5, 5' are secured to the cover plate 6 by terminal screws 9 upon which nuts 10, with permanently attached resilient lockwashers 11, are threaded. Terminal lugs 12 are secured to the screws 9 by similar

40 nut-lockwasher assemblies 10, 11 for receiving leads of the control circuit by which current is supplied to melt the fuse wire 8, thereby conditioning the relay for operation as the resilient arms spring apart to permit engagement of the relay contact arm 3 with contact 4 or 4' when

45 50 55

the current through the relay coil 1 reaches a preselected value.

The cover plate 6 is preferably a transparent plastic, and it is detachably secured to the upper flange of the metal wall 13 of the relay case to permit removal for a checking of the relay. The cover plate is resiliently compressed against the flange by screws 14 that have heads soldered or brazed to the lower face of the flange, and unitary self-locking locknut assemblies comprising nuts 10 and resilient lockwashers 11 of the same type but of larger size than the nut-lockwasher assemblies 10, 11 that are used on the screw terminals 9.

In accordance with this invention, the nuts 10 and spring lockwashers 11 are separately formed and permanently connected by welding, brazing or soldering to form a unit that facilitates the application and removal of the nuts and lockwashers, and that substantially precludes the loss of the relatively minute lockwashers within the relay case. As illustrated on an enlarged scale in Figs. 3 and 6, the spring lockwasher 11 is secured to the nut 10 by a spot weld 15 at or adjacent an end of the lockwasher. The lockwasher 11 is so shaped as to avoid a "bite" on the cover plate 6 or other surface that it may engage but, as shown in Figs. 4 and 7, the lockwasher 11a may be shaped to obtain a "bite" on the engaged surface. As illustrated in Figs. 5 and 8, a radially-split and helical lockwasher 11a may be secured to the nut 10 by a spot weld 15a at a point substantially midway between the ends of the lockwasher. The ends of the lockwasher are overlapped in conventional manner, and both ends are spaced from the adjacent end surface of the nut 10.

The bolted connections do not loosen under vibration nor as a result of "bolt stretch" or a shrinkage of non-metallic parts such as, for example, a relay cover plate 6 of transparent plastic material. The helical spring washers 11 or 11a afford a "follow up" or resilient clamping action since the washers are coaxial with the nuts and are not threaded, i. e. the internal diameter of the washer is somewhat greater than the root diameter of the threads of the associated nut.

The spring washers may be attached to screws,

for example as shown in Fig. 9, by welding or soldering the lockwasher 11 to the lower face of the head of the screw 16.

It is convenient to employ the conventional lockwashers that are formed as one turn of a helix of resilient metal but, as shown in Fig. 10, a resilient locking element 17 of substantially less angular extent than 360° may be secured to a nut 10 by a spot weld 18.

The several illustrated embodiments are typical of the invention and it is to be understood that other variations are possible within the scope of the invention as set forth in the following claim.

I claim:

A self-locking assembly for threaded engagement with a screw; said assembly comprising a nut with a threaded bore and a flat inner end surface, and a lockwasher consisting of a one-turn helix of resilient metal having a point substantially midway of the ends thereof welded to said flat inner end surface of the nut, the ends of the lockwasher being overlapped and both ends being spaced from the adjacent flat end surface of the nut, the area of a face of said lockwasher being not less than the area of said end surface of the nut and the internal diameter of the lockwasher being greater than the root diameter of the threads of the nut.
